ABSTRACT OF THE DISCLOSURE

A casket formed from prefabricated sheet metal components which are readily assembled together to form a rigid and sturdy construction. The side and end walls are formed from panels having angularly inwardly directed flanges at each end, inwardly directed flanges at the bottom, and flanges at the top defining a top rim. Corner fixtures are provided overlying the outer surfaces of the panels, and tension members are connected to the fixtures so as to constrict the panels constantly around the outer perimeter, thereby holding the panels rigidly together. The tension members are arranged so that they also function as handles for carrying the casket. A bottom panel is supported on the inwardly directed flanges at the bottom of the panels, and reinforcing ribs and bottom members are also provided.

Cross-reference to related application

This application is a continuation-in-part of pending application Ser. No. 634,685, filed Apr. 28, 1967, now abandoned, for "Set-Up Casket with Handle-Bar Ties."

Background of the invention

The present invention relates to caskets, and more particularly to caskets which can readily be assembled from prefabricated components.

It is the conventional practice when manufacturing caskets for a manufacturer to fabricate the shell and ship it to an upholsterer who finishes the casket. From an economic standpoint, it would be desirable to ship the shell in prefabricated components for many reasons. The cost of freight from manufacturer to upholsterer is reduced, the storage space is reduced, and the need for skilled labor in assembly is eliminated.

Summary of the invention

The present invention is directed to a casket which is designed to require for its assembly a minimum of skills on the part of those assembling the casket at any desirable location, and when so formed will provide a sturdy and rigid construction.

According to one form of the present invention, a casket is provided comprising side and end panels connected together to define a rectangular enclosure, each of the panels having an angularly inwardly directed flange at each of its ends in facing relationship with corresponding flanges of the adjacent connected panels. A separate fixture is positioned at each corner overlying the outer surfaces of the two associated panels forming such corner, and a pair of tension members are connected to each of said separate fixtures. One of the tension members of each pair extends in parallel relationship with one associated panel and extends toward the fixture at the other end of the associated panel. The other tension member of each pair similarly extends in parallel relationship with the other associated panel toward the fixture at the other end of such associated panel. Means are provided for securing the tension members in place

under tension so that the tension forces in the tension members constantly act on the fixtures to hold the panels under compression in the form of the rectangular enclosure. In the preferred form of the invention the tension members are located so that they also function as the handles for lifting the casket.

The means for securing each of the tension members in place is an interlocking connection wherein the tension members are initially installed in place by insertion of a pin on the tension member into an enlarged hole in the fixture, and thereafter when all tension members have been installed in place, the tension members can be shifted upwardly to a second or locked position in the fixture wherein all such tension members have been placed in tension, and correspondingly, the panels have been placed under compression, so that a rigid rectangular structure is provided. This structure for assembling the components is characterized by its simplicity so that no special skills are required for carrying out the assembling operation.

Accordingly, it is one of the objects of the present invention to provide an improved casket formed from prefabricated parts which can readily be assembled at any desired location to provide a rigid and sturdy casket. 25 Any combination of tension members and brackets which put the flanges, or the equivalent of flanges, in compression can be used in forming the casket of this invention. It is a further object of the present invention to provide a casket in which the conventional handle or carrying 30 bars perform not only their usual function of being handles, but also coact with certain corner fixtures to tie together the side and end panels into a rigid rectangular structure.

Other objects of this invention will appear in the following description and appended claims, reference being had to the accompanying drawings forming a part of this specification wherein like reference characters designate corresponding parts in the several views.

Brief description of the drawings

40 FIG. 1 is a top plan view of an assembled casket, embodying one form of the present invention.

FIG. 2 is a broken fragmentary side elevation showing one end and a central portion of the casket;

45 FIG. 3 is a section taken on the line 3—3 of FIG. 1;

FIG. 4 is a fragmentary section taken on the line 4—4 of FIG. 1;

FIG. 5 is an enlarged fragmentary top plan view with portions broken away and in section showing details of 50 the corner structure for assembling the casket;

FIG. 6 is an exploded fragmentary perspective view of certain of the components forming the corner structure of FIG. 5;

FIG. 7 is a fragmentary section taken on the line 7—7 55 of FIG. 5;

FIG. 8 is a perspective view showing a fragment of a corner securing means which may be used in assembling the panels;

FIG. 9 is a fragmentary section similar to FIG. 5, 60 but showing a modified arrangement of tension members and corner fixtures for assembling the casket;

FIG. 10 is a fragmentary section taken on the line 10—10 of FIG. 9; and

FIG. 11 is a fragmentary top plan view of a modified 65 form of the casket shown in FIG. 1.

Description of the preferred embodiment

Before explaining the present invention in detail, it 70 is to be understood that the invention is not limited in its application to the details of construction and arrangement of parts illustrated in the accompanying drawings, since the invention is capable of other embodiments and

of being practiced or carried out in various ways. Also, it is to be understood that the phraseology of terminology employed herein is for the purpose of description and not of limitation.

Referring to the drawings, the embodiment of the invention shown in FIGS. 1-8 will now be described in greater detail. As there shown, the casket 10 includes side panels 12 and 14 and end panels 16 and 18 which are arranged to define a rectangular enclosure. Each of these panels is similarly constructed so as to have angularly inwardly directed flanges at each end, as shown at 20 and 22 in FIG. 5 with respect to panels 12 and 16. The panels also have inwardly turned flanges extending lengthwise along the bottom edges, such as are shown at 24 (FIG. 3) and 26 (FIG. 6). A bottom panel 28 is positioned on the inturned bottom flanges and is retained thereon in a suitable manner, such as is shown in FIG. 3 with respect to the flange 24. Corner fixtures 30, 32, 34 and 36 overlie the outer surfaces of the panels forming the various corners, and tension members 38, 40, 42 and 44 are connected at their opposite ends to the fixtures at each of the corners. As will presently be described, the manner of securing the tension members to their associated corner fixtures is such as to place the tension members in a state of tension so that they will continuously act on the fixtures to hold the panels together in a state of compression so as to provide a sturdy and rigid structure. The side panels 12 and 14 have mounted intermediate their ends a plurality of fixtures 46 which are notched on their undersides as at 48 to provide surfaces in which the associated tension members 40 and 44 can be seated. Any suitable means may be employed for securing the fixture 46 to their associated panels, such as tabs 49 which may be passed through slots in the panels.

The four corner fixtures 30, 32, 34 and 36 are constructed the same and are interchangeable, and therefore, only corner fixture 36 will be described in detail. Also, only the steps of assembling this fixture with its two associated panels 12 and 16 will be explained. As can be seen best in FIG. 6, the corner fixture 36 has been formed to have at its upper end two flanges 51 which are bent downwardly at the appropriate time to form two box-shaped channel portions 50 and 52 for receiving in essentially telescoping fashion the top box channel sections 54 and 56 of panels 12 and 16. Likewise, the lower end of corner fixture 36 has been formed with channel portions 50 and 60 for receiving in telescoping fashion respectively the bottom channel portions 62 and 64 of the panels 12 and 16. When the components are telescoped together in this manner, the midportions 66 and 68 will pivot over the outer surfaces of the panels 12 and 16 and can be connected thereto by the tongues 70 which are adapted to be inserted through slots 72 in each of the panels. These slots preferably will be oversized for a purpose to be described.

Thus, as an initial step in assembling the casket 10, the four panels 12, 14, 16 and 18 can be arranged to stand in positions to define a rectangular enclosure and the corner fixtures can be telescoped endwise onto the adjacent corners and connected in the manner described above in connection with the fixture 36.

When assembling the corner fixtures, it is preferred that a gasket member 74 (FIG. 5), formed of polyethylene, neoprene or similar material, be positioned between the angularly inwardly directed flanges 20 and 22, and each of the other corresponding flanges at the other corners. Then as shown in FIG. 8, a clip 76, preferably formed of spring steel, can be slipped over the flanges 20 and 22. The clip 76 comprises a U-shaped central member having legs 78 with outwardly directed clamping members 80. A tongue 82, formed in each of the legs 78, springs through the perforations 84 formed in the flanges 20 and 22 and penetrates the gasket material 74 to form a temporary securing means during assembly of the cor-

ner structure. When this is repeated at all four corners, the side and end panels are assembled in a preliminary stage and are then ready to be brought into final assembly by application of the corner members 30, 32, 34 and 36, and thereafter, the tension members 38, 40, 42 and 44.

The tension members are constructed with a pin 86 extending laterally from each end, and each such pin has a retaining head 88 at its outer end. As shown in FIG. 7, the head 88 of the pin 86 can be inserted initially into the lower enlarged portion of an aperture 90. When both pins of all tension members have been inserted in this manner into apertures in fixtures at opposite ends of the four panels, the tension members can be raised upwardly so that the pins slide over the cam surfaces 92 and then seated in the upper portion of the apertures 90. The dimensions of the tension members and panels are such that when moved upwardly in the described manner, the tension members will be placed in tension, thereby pulling the corner fixtures tightly against the ends of the panels, and the latter will be placed in a state of compression. Thus, the components will be locked securely together. As previously indicated, the slots 72 for the tabs 70 are enlarged so that the tension forces of the tension members are transmitted to the corner fixtures and the latter can move a limited amount relative to the panels so that the tension members and corner fixtures and the latter can move a limited amount relative to the panels so that the tension members and corner fixtures tightly bind the panels together in the shape of the rectangular enclosure defined by the upright panels.

It will be recognized that the corner fixtures need not have the specific shape shown, but the fixtures preferably will include a socket such as is shown at 94 in FIG. 6, for example, into which the end of a tension member 44 can be seated and in the inner wall of which will be located the aperture 90. However, if desired, a modified arrangement such as is shown in FIGS. 9 and 10 may be employed. As there shown the corner fixture 136 has apertures 190 formed therein for receiving the ends of tension members 138 and 144. Similar to the previously described embodiment, the aperture 190 has a lower enlarged portion, and the tension member 144 must be raised upwardly over the cam surface 192 in order to lock the member 144 in tension in the upper portion of aperture 190.

Also, it is not essential that the tension members extend from one corner fixture to another corner fixture. As shown in the embodiment of the casket 210 shown in FIG. 11, tension members 238, 240 and 244 are operatively connected in tension to corner fixtures 230 and 236 (which may be the same as corner fixtures 30 and 36), and to intermediate fixtures 245 and 246. The latter are constructed with apertures similar to those in corner fixtures 230 and 236 so that members 240 and 244 can be locked in tension and thereby, corner fixtures 230 and 236 can be pulled by tension members tightly in place against the ends of the panels forming the corners in much the same manner as was done in the embodiments of the invention previously described.

The bottom panel 28 used with any of the described embodiments preferably will have stiffening ribs 96 extending its full length. Also, if desired, supplementary bottom panels 98 may be used having transverse ribs 100. The panels 98 may be secured in place in any suitable manner, such as by the clips 102. Upright stiffening members 104 (FIG. 3) may also be used and they can be suitably secured in place by the clips or tabs 49, used to secure the fixtures 46 in place.

From the foregoing description it will be understood that a casket has been provided which can be prefabricated and shipped economically in an unassembled state in convenient sized packages of minimum weight to any desired location where the caskets can quickly and easily be assembled to form rigid, relatively lightweight struc-

tures. Furthermore, the securing means comprises members which are stressed when being locked in place so as to maintain constantly a holding action on the assembled parts. It is to be understood that while angularly directed flanges are illustrated and are preferred, any suitable means can be employed for transmitting tension forces to the walls of the casket so as to compress the end walls against the side walls or vice versa.

What is claimed is:

1. A casket comprising side and end panels arranged in an abutting relation to define an enclosure, a plurality of tension members, and means for securing said tension members in place on said panels and under tension so that the tension forces in said tension members constantly act to hold the panels together in compression in the form of the enclosure, said means including a plurality of fixtures mounted in fixed positions on the exterior surfaces of said panels and connected to said tension members, and an interlocking structure for securing each tension member to a fixture defining a first position for assembly purposes wherein said tension member is connected initially to the fixture in an untensioned state, and a second position above said first position wherein said tension member is locked in tension as an incident to upward movement of the tension member relative to the fixture so that the casket can be carried by lifting the tension members without releasing the tension forces of the tension members.

2. A casket according to claim 1 wherein each of said panels has inwardly directed flange means at its ends arranged in engagement with corresponding flange means on the adjacent panels.

3. A casket according to claim 2 wherein each of said fixtures is located at a corner of enclosure in overlying relation with the two associated panels forming said corner, each of said tension members extending substantially parallel to one of said panels between a pair of said fixtures.

4. A casket according to claim 3 further including additional fixtures mounted on the side panels between the ends thereof and having notches opening in a downward direction, some of said tension members being seated in said notches for transmitting vertical lifting forces to the side panels.

5. A casket according to claim 2, wherein said tension members are spaced from their associated parallel panels for at least a portion of their lengths so that the tension members can be used as handles for lifting the casket.

6. A casket according to claim 2, wherein said flange means extends angularly inwardly and further including clamp means securing together engaged flange means.

7. A casket according to claim 1, wherein said panels have inwardly directed lengthwise flanges on the bottom edges thereof, and a bottom panel overlies said lengthwise flanges and is supported thereby.

8. A casket according to claim 7, wherein said bottom panel has longitudinal stiffening ribs, and further includ-

ing at least one stiffening member extending transversely of said bottom panel and secured to opposite side panels.

9. A casket comprising side and end panels arranged in abutting relation to define an enclosure, a plurality of tension members, and means for securing said tension members in place on said panels and under tension so that the tension forces in said tension members constantly act to hold the panels together in compression in the form of the enclosure, said means including a plurality of fixtures mounted in fixed positions on the exterior surfaces of said panels and connected to said tension members, some of said fixtures being mounted on the side panels between the ends thereof and connected to the ends of some of said tension members.

10. A casket comprising side and end panels arranged in abutting relation to define an enclosure, each of said panels having inwardly directed flanges at its ends in engagement with corresponding flanges on the adjacent panels, a plurality of tension members, and means for securing said tension members in place on said panels and under tension so that the tension forces in said tension members constantly act to hold the panels together in compression in the form of the enclosure, said means including a plurality of fixtures mounted in fixed positions

20 on said panels and connected to said tension members, each of said fixtures being located at a corner of the enclosure in overlying relation with the two associated panels forming said corner, each of said tension members extending substantially parallel to an associated one of said panels between a pair of fixtures and being spaced from such associated parallel panel for at least a portion of its length so that the tension members can be used as handles for lifting the casket, an interlocking structure between the member and the fixture defining a first position for assembly purposes wherein said tension member is connected initially to the fixture in an untensioned state, and a second position above said first position wherein said tension member is locked in tension as an incident to upward movement of the tension member relative to the fixture so that the casket can be carried by lifting the tension members without releasing the tension forces of the tension members.
